United States Patent Office.

JULIUS BENEDICT, OF BROOKLYN, NEW YORK.

Design No. 3,574, dated July 6, 1869.

DESIGN FOR SASH-WEIGHTS.

The Schedule referred to in these Letters Patent and making part of the same.

To all whom it may concern:

Be it known that I, JULIUS BENEDICT, of Brooklyn, in the county of Kings, and State of New York, have invented a new and valuable Design for Sash-Weights; and I do hereby declare that the following is a full, clear, and exact description of the same, reference being had to the annexed drawings, making a part of this specification.

Figure 1, of the drawings, is an external view of my sash-weight;

Figure 2 is a longitudinal section thereof; and

Figure 3 is a view of the grooved head of the sash-

weight, showing the means provided for attaching the cord to the same.

What I claim as my invention, and desire to secure by Letters Patent, is—

The design for sash-weight, herein described and shown.

In testimony that I claim the above, I have hereunto subscribed my name, in the presence of two witnesses.

Witnesses:

WM. G. SMITH,
JAMES DALY.
